UNITED STATES PATENT OFFICE.

CHARLES WESLEY WALTON, OF PRINCETON, INDIANA, ASSIGNOR OF ONE-HALF TO F. H. MAXAM, OF SAME PLACE.

DESIGN FOR A NECKTIE-BAND HOLDER.

SPECIFICATION forming part of Design No. 25,659, dated June 23, 1896.

Application filed May 7, 1896. Serial No. 587,872. Term of patent 14 years.

To all whom it may concern:

Be it known that I, CHARLES WESLEY WALTON, a citizen of the United States, residing at Princeton, in the county of Gibson and State of Indiana, have invented a new and original Design for Necktie-Band Holders, of which the following is a specification.

This invention relates to a new and original design for necktie-band holders, and it has for its object to provide a design of this character that shall be both useful and ornamental.

The leading feature of the design resides in a pair of flat reversely-disposed segmental figures arranged slightly out of alignment and in parallel planes, and a web portion arranged between said figures and merging at its ends into the chords or straight sides of said figures.

In the drawings, Figure 1 is a perspective view of a necktie-band holder embodying the

herein-described design. Fig. 2 is a front elevation thereof. Fig. 3 is a sectional view.

Referring to the accompanying drawings, 1 designate a pair of flat reversely-disposed 25 segmental figures having the chords or straight edges 2. The segmental figures 1 are arranged slightly out of alignment and in parallel planes, and an intermediate web portion 3 is arranged between the figures 1 and merges 30 at its ends into the said chords or straight edges 2.

What I claim is—

The design for a necktie-band holder herein shown and described.

In testimony that I claim the foregoing as my own I have hereto affixed my signature in the presence of two witnesses.

CHARLES WESLEY WALTON.
